UNITED STATES PATENT OFFICE

GEORGE N. WILLIAMS, OF KOKOMO, INDIANA, ASSIGNOR TO CONTINENTAL STEEL CORPORATION, OF KOKOMO, INDIANA, A CORPORATION OF INDIANA

MACHINE FOR MANUFACTURING LEAD-HEAD NAILS

Continuation of application Serial No. 254,529, filed February 15, 1928. This application filed August 12, 1929. Serial No. 385,393.

This invention has to do with the manufacture of what is now commonly known as "lead-head" nails, i. e., weatherproof nails which have soft metal washers encircling the nail heads and portions of the shank immediately next the nail head. Such nails are now extensively employed for fastening corrugated and flat sheet roofing or siding to the underlying rafters, purlins or studs.

The principal object of the invention is to provide a machine for automatically applying the soft metal, such as lead, to the head end of the nails by driving the nails through a strip of lead and through such action detach sufficient of the strip to provide the "lead-head"; or to drive the nails through a spherical mass of metal, each mass including the necessary material to provide the "lead-head".

The invention has for a further object to provide in a machine of the character described, means to feed the nails to driving position, means to feed the metal for the "heads" to penetrating position, by the nails, means to center the nails, separable dies for forming the "lead-heads" on the nails, a driving means, and a delivery means for the finished "lead-headed" nails.

Other and further objects will more fully appear from the following description.

That the invention may be more fully understood, reference is had to the accompanying drawings forming part of this description, illustrating a preferred embodiment of the invention, in which:

Fig. 1 is a front elevation, on a greatly reduced scale, of a machine embodying my invention;

Fig. 2 is a side elevation of Fig. 1, as the same would appear, looking at the right hand side of such figure;

Fig. 3 is a side elevation of Fig. 1, as the same would appear, looking at the left hand side of such figure;

Fig. 4 is a detail elevation of the operating means for the metal strip feeding means;

Fig. 5 is an enlarged vertical sectional view showing the nail feed, the nail center-

ing means, nail driving means, dies and nail delivery means;

Fig. 6 is a transverse sectional detail view showing the dies and associated parts, the dies being in open position and the position of a nail just preceding the nail driving operation;

Fig. 7 is a sectional detail view, somewhat similar to Fig. 6 but with the dies closed and the nail having been driven and the nail "lead-headed";

Fig. 8 is a detail in plan, partly in section, showing the nail centering means and a metal strip, as the same would appear if taken on the line 8-8, Fig. 6;

Fig. 9 is a vertical sectional view, somewhat similar to Fig. 5, except that means is shown for feeding spherical masses of soft metal, such as lead, to provide the "lead-head" for the nails;

Fig. 10 is a detail section, in plan, of the nail centering means, as the same would appear if taken on the line 10-10, Fig. 9;

Fig. 11 is a detail section, in plan, of spherical mass centering means, as the same would appear if taken on the line 11-11, Fig. 9, and

Fig. 12 is a plan view and an elevation, partly in section, enlarged, showing a "lead-headed" nail, a product of the within described machine.

Like characters of reference denote corresponding parts throughout the figures.

Nails such as are "lead-headed" on my machine may be seen in Fig. 12, comprising a shank *a* having preferably a flat metallic head *b* formed from the body of the material from which the nail is made and the head and part of the shank adjacent thereto embraced by a soft metal washer *c*, preferably of "lead".

Referring to the machine, the same includes legs 1 supporting a bed 2 on which is supported in fixed position a die-plate 3 formed or provided with a guide-way 4 in which are arranged for movement, toward and from each other, corresponding die members 5, 5, the meeting ends of which have sectional nail seats 6, preferably shaped so that when caused to embrace a nail they receive, in addition

- to the head of a nail and shank portion adjacent thereto, also receive, embrace and press the metal *c*, providing the "lead-head" about the nail head *b*, in substantially the 5 manner and form shown in Fig. 12. Further, the die-plate 3 has a delivery opening in communication with the guide-way 4 for the dies 5 and arranged in said delivery opening and inclined outwardly and downwardly 10 are spaced plates or bars 8 which provide a chute to deliver by gravity the "lead-headed" nails, to any suitable receptacle. The plates or bars 8 being spaced apart only a sufficient distance to receive the shanks of 15 the nails therebetween with the "lead-heads" resting and sliding on the upper edges of said plates or bars, as shown. Also, as shown in Figs. 6 and 7, the inner ends of the dies 5 are off-set to receive the upper receiving ends of the plates or bars 8, when the dies 20 are closed or are in forming position.
- Rising from the bed 2 is a supporting standard or frame 9, from the front face of 25 which is supported a guiding head 10, the lower guiding portion of which terminates immediately above and is centered over the meeting position of the inner ends of the dies 5, and to and below the lower end of said guiding portion is disposed the centralizing means, to be described, for centering the 30 nails as they are successively driven through the soft metal to attach the same thereto.
- Supported for oscillation at the head end 35 of the frame 9 is a hopper 11 for holding, in bulk, the nails, to be "lead-headed", and this hopper is so arranged that oscillation thereof will agitate the nails so that they are successively discharged from the hopper onto the inclined guide 12, see Fig. 2, and as the 40 nails reach the end of said guide, by reason of gravity, they are picked up by the notched disc 13 and discharged, one at a time, into the tube 14 which feeds the nails into the guide 15 in the guiding head 10 which delivers the said nails into the perpendicularly disposed delivery opening 16 in said guiding head 10. The opening 16 is the continuing 45 lower portion of a guide-way 17 in which is reciprocally arranged a driving plunger or hammer member 18, to the upper outer end of which is connected links 19 to which, in turn, is pivotally connected a lever 20 fulcrumed to the frame 9, at 21. This lever is the means through which movement is positively imparted for oscillating the hopper 11, for driving the plunger or hammer 18 and for moving the dies 5 toward each other. 50
- 22 designates a driving shaft journaled in suitable bearings on the rear of the machine frame and said shaft may receive its power from a suitable source through a pulley wheel 23 secured to said shaft. The said shaft has connected thereto an eccentric 55 24 which in turn is operatively connected with the lever 20 through a connecting member 25, and 26 is a member connecting the lever 20 with the hopper 11 for oscillating the latter with each reciprocation of said lever. Secured to the said shaft 22 is a bevel gear pinion 27 with which meshes a bevel gear 70 wheel 28 on the lower end of a shaft 29 to which is secured the notched disc 13, see Fig. 2.
- Journaled longitudinally of and in suitable bearings at the rear of the bed-plate 3 75 is a rock shaft 30. At a suitable point to said shaft 30 is connected a crank-arm 31 to which is pivotally connected one end of a pitman bar 32 which, at its upper end has a pivotal connection with the lever 20, see Fig. 80 2. To the opposite ends of said rock shaft 30, at points beyond the outer ends of the die members 5, are secured lever arms 33 having the cam or beveled faces 34, which faces are adapted to ride against and coact with 85 similar faces on plates 35 secured to the outer ends of the die members 5, see Figs. 6 and 7. The die members 5 are normally held opened and are separated on the formation of a "lead-head" by means of springs 36 which are 90 carried in recesses 37 in the bed-plates 35. The dies being moved to closed position in pre-determined time for the driving of a nail, by the rocking of the shaft 30 and the movement of the levers 33 against the plates 35. 95
- In the form of the machine described, the "lead-heads" for the nails are provided by the strip of metal A. This strip is carried on a spool B, see dotted lines, Fig. 1, the spindle of which is removably journaled in a support C secured to a side of the machine. The strip A is fed longitudinally of and across the upper surfaces of the dies 5, by means of feeding rollers 38 carried by shafts 39 which are spring mounted at one end in a frame 40 100 and journaled at their opposite ends in a standard 41, and the shafts geared together by gearing 42. To actuate these shafts, one is provided with a ratchet wheel 43 operated by a ratchet-pawl 44 carried by a lever 45 105 fulcrumed on a shaft 39 and having an end riding on and adapted to be oscillated by a cam 46 on the driving shaft 22. The lever 45 is maintained in contact with the cam 46 by a spring 47 and a spring 48 engaging the 110 ratchet wheel 43 holds it to its forward movement and prevents backward movement thereof. The strip A is guided to position over the dies 5 and held to position by means of guides 49, arranged substantially as shown 115 in Figs. 5, 6 and 7.
- The centralizing means for the nails to guide them to position when penetrating the strip A, comprises a housing 50 secured to the lower delivery end of the guiding frame 120 10. This housing includes an opening 51 disposed axially below the opening 16 and intercepting this opening are a plurality of radial guide openings 52 in which are movable the centering members 53 held to operative posi- 125 130

tion by springs 54, bearing, one end against such members and at their opposite ends against plugs 55 threaded into the outer ends of the openings 52. The inner ends of the members 53 have tapered sides to adapt them to lie adjacent each other, see Fig. 8, and the upper inner surface of each member is tapered downwardly and inwardly to provide a seat to receive the pointed ends of the nails, that the centering means in association with the opening 16 will retain the nails perpendicularly, see Fig. 6, while the plunger or hammer 18 acts to engage and drive the nail downwardly, which action will cause a separation or spreading of the members 13 permitting the nails to be forced down through the strip A, cutting enough of the metal from the strip to provide the soft washer c for the head of the nail and to embrace the same in manner shown in Fig. 12 through and by means of the action of the dies 5 between which the nail and metal is forced, as shown in Fig. 7.

In the operation of the machine thus far described, assuming the driving shaft 22 to be operated, the lever 20 imparts oscillatory movement to the hopper 11 to cause the discharge of the nails which are fed to the notched disc 13 in the manner seen in Fig. 2 and said disc delivers the nails point downward into the tube 14 through which they find their way into the delivery opening 16 where the nails drop point downward resting on the seat formed by the centralizing members 53, see Fig. 6. The lever 20 reciprocates the plunger or hammer 18 in timed relation to the delivery of each nail onto the centralizing device, and said plunger or hammer as it reaches the lower end of its stroke drives the nail past the members 53, forcing these outwardly against the tension of the springs 52, which permits the nail to be driven through the strip A carrying with it sufficient of the metal of the strip A to provide the metal washer c. By this time the dies 5, through the instrumentalities described, have been moved to the closed position in Fig. 7, so that the continued downward movement of the nail and washer c, through the action of the plunger or hammer results in compressing the washer c about the head of the nail and the shank next adjacent thereto, substantially as seen in Fig. 12. On the formation of the "lead-head" on the nail the dies are released so that the springs 36, which have been compressed, act quickly to release the dies from the nail and return the same to open position, seen in Fig. 6. There can be no lateral movement of the "lead-headed" nail, as its shank is positioned between the plates or bars 8 and as a result the completed nail drops into position with its head resting on the upper edge of the plates or bars 8, in which position the nail moves by gravity along said plates or bars to be received into some suitable recep-

tacle. Between each driving operation of the plunger or hammer, the strip is fed by the feeding rollers to present material from which may be cut the washer c. The operation is continuous with nails being delivered successively to driving position in timed relation to the operation of the several parts or mechanisms of the machine.

In the event it is desirous or expedient to form the washers c from a spherical mass of metal instead of from a strip of metal A, as has been described, the strip feeding means and guiding means for such strip would be omitted and spherical mass feeding means and a centering means for the mass would be incorporated, in manner I shall now explain, reference being had particularly to Figs. 9, 10 and 11.

To the upper and front face of the guiding-head 10 is mounted a hopper 60 from which depends a delivery spout 61 into which the spherical masses D are delivered one at a time, and these are discharged from said spout, by gravity, into an extension of the delivery opening 16. These spheres are valved from the hopper 60 into the spout 61 by means of a slide valve 62 having a pocket 63 adapted to pick up the spheres with each reciprocation, and deliver the same into the upper end of said spout 61. Said valve is reciprocated by means of a crank 64 connected thereto, which in turn has connection with a lever arm 65 connected to the upper end of the plunger or hammer 18. A slotted connection is provided between the crank 64 and the valve 62 and between the lever arm 65 and the plunger or hammer, as shown, to compensate for the play required between the movement of these parts and prevent binding thereof.

In place of the centralizing housing 50, but corresponding thereto, is a centralizing housing 66 secured to the lower end of the head 10, with a discharge opening 67 in axial alignment with and forming an extension of the delivery opening 16. In superimposed and spaced relation in said housing are provided two sets of centralizing means, in all respects similar to that shown in Fig. 8, comprising as one set the members 68 and as the other set the members 69, each radially movable and spring held like in the set previously described and shown in Fig. 8. In the one set, the members 68 provide a seat for the reception of the pointed ends of the nails and in the other set, the members 69 provide a seat for the reception of the spheres D; the said spheres passing from the spout 61 through a guiding opening 70 in the housing 66, into the discharge opening 67 in said housing, resting in the seat formed by the members 69.

The nail on being driven downwardly by the hammer is caused to penetrate a sphere D and carry it forward into the dies where the washer c is formed thereon in manner pre-

viously explained. The centralizing means of each set, separating under pressure of the nail and returning to receiving position immediately on the passage of the nail to the dies and the receding of the plunger or hammer, substantially as heretofore disclosed.

I have elected to show the centralizing means of Figs. 10 and 11 as containing fewer of the centralizing members than shown in Fig. 8, to illustrate that a fewer or greater number may be employed, as desired. Furthermore, it will be obvious that while I have elected to show the driving movement of the plunger or hammer as perpendicular, its movement may be in a horizontal direction, or otherwise, as may be found desirable or expedient.

This application is a continuation of the application filed by me February 15th, 1928, bearing Serial No. 254,529.

What I claim is:

1. In a machine for "lead-heading" nails, in combination, means to successively feed nails to position preparatory to being headed, means to feed a lead strip across the path of projection of the nails and from which the "lead-heads" are formed, means to drive the nails through the lead strip to heading position and simultaneously sever from said strip sections of material for the "lead-heads," laterally movable header means adapted when moved to operative position to form the said sections of material about the nail heads, and means to prevent lateral movement of the nail during the lateral movement of the forming means to inoperative position.

2. In a machine for "lead-heading" nails, in combination, means to successively feed nails to position preparatory to being headed, means to center the nails at driving position, said centering means including a plurality of radially movable tensioned fingers having their inner ends formed to engage and hold the nail throughout the circumference of the shank thereof, means to feed a lead strip across the path of projection of the nails and from which the "lead-heads" are formed, means to drive the nails through the lead strip to heading position and simultaneously sever from said strip sections of material for the "lead-heads," laterally movable means adapted when moved to operative position to form the said sections of material about the nail and means to prevent lateral movement of the finished nail when the forming means is moving laterally to its inoperative position whereby clogging of said forming means is eliminated.

3. In a machine for "lead-heading" nails, in combination, means to successively feed nails to position preparatory to being headed, means to feed a lead strip across the path of projection of the nails and from which the "lead-heads" are formed, means to drive

the nails through the lead strip to heading position and simultaneously sever from said strip sections of material for the "lead-heads", opposed laterally movable header means adapted when moved to operative position to form the said sections of material about the nail heads, a discharging means for the "lead-headed" nails, said discharging means engaging the nail during the lateral movement of the forming means to its inoperative position whereby to prevent lateral movement of the nail.

4. In a machine for "lead-heading" nails, in combination, means to successively feed nails to position preparatory to being headed, means to center the nails at driving position, said centering means including a plurality of radially movable tensioned fingers having their inner ends formed to engage and hold the nail throughout the circumference of the shank thereof, means to feed a lead strip across the path of projection of the nails and from which the "lead-heads" are formed, means to drive the nails through the lead strip to heading position and simultaneously sever from said strip sections of material for the "lead-heads," laterally movable means adapted when moved to operative position to form the said sections of material about the nail heads, and means beneath the forming means to prevent lateral movement of the finished nail when said forming means is moved laterally to its inoperative position.

5. In a machine for "lead-heading" nails, in combination, means to successively feed nails to position preparatory to being headed, means to feed a lead strip across the path of projection of the nails and from which the "lead-heads" are formed, means to drive the nails through the lead strip to heading position and simultaneously sever from said strip sections of material for the "lead-heads," laterally movable separable die members adapted when moved to operative position to successively act on the nails and the said sections of material to form the material about the heads of said nails, and means to prevent lateral movement of the nail when said die members are moved laterally to their inoperative position whereby to prevent clogging of said die members by the finished nail.

6. In a machine for "lead-heading" nails, in combination, means to successively feed nails to position preparatory to being headed, means to support and center the nails at driving positions, said centering means including a plurality of radially movable tensioned fingers having their inner ends formed to engage and hold the nail throughout the circumference of the shank thereof, means to feed a lead strip across the path of projection of the nails and from which the "lead-heads" are formed, means to drive the nails

- through the lead strip to heading position and simultaneously sever from said strip sections of material for the "lead-heads", laterally movable separable die members 5 adapted when moved to operative position to successively act on the nails and the said sections of material to form the material about the heads of said nails, means to close and open said dies preparatory to and after "head" forming, and means to receive and discharge the "headed" nails, said receiving means being disposed transversely of the path of movement of said die members to prevent lateral movement of the nail when the 10 die members are moved laterally to their open inoperative position whereby to prevent clogging of the die members by the finished nails.
7. In a machine for "lead-heading" nails, 20 in combination, laterally movable separable die members normally held in open inoperative position, means to feed a continuous strip of soft metal across the opening between said members, means to successively project nails through said strip and into head forming position between said dies and to simultaneously detach from said strip sections of the strip for "heading" the nails, means to move the dies toward each other 25 whereby to act on the sections of material to form the material about the heads of the nails, and means to prevent lateral movement of the nail when the dies are moved laterally to their open inoperative position 30 whereby to prevent clogging of said dies by the finished nail.
8. In a machine for "lead-heading" nails, 35 in combination, laterally movable coacting die members, means to feed a continuous strip of soft metal across the point of coaction of said members, means to successively deliver nails to driving position through said metal strip, means to drive the succeeding nails through said strip at successively different points throughout the strip and to simultaneously sever from the strip sections of the metal to form the "heads", means to cause a coaction of the die members to form the sections of metal as "heads" about the 40 respective nails, and means to prevent lateral movement of the nail when the die members are moved laterally to their inoperative position whereby to prevent clogging of said die members by the finished nails.
- 5 9. In a machine for "lead-heading" nails, 45 in combination, means to successively feed nails to position preparatory to being headed, means to feed heading material across the path of projection of the nails and from which the "lead-heads" are formed, means to drive the nails through the material to heading position, laterally movable means to form said material about the nail heads, means to move the forming means laterally into and out of 50 operative position, and means to prevent lat-
- eral movement of the nail when the forming means is moved laterally to its inoperative position whereby to prevent clogging of the forming means by the finished nail.
10. In a machine for "lead-heading" nails, 70 in combination, means to successively feed nails to position preparatory to being headed, means to center the nails at driving position, said centering means including a plurality of radially movable tensioned fingers 75 having their inner ends formed to engage and hold the nail throughout the circumference of the shank thereof, means to feed heading material across the path of projection of the nails and from which the lead-heads are formed, means to drive the nails through the material to heading position, laterally movable means adapted when moved to operative position to form the material about the nail heads and means to prevent 80 lateral movement of the nail when the forming means is moved laterally to its inoperative position whereby to prevent clogging of the forming means by the finished nail.
11. In a machine for "lead-heading" nails, 85 in combination, means to successively feed nails to position preparatory to being headed, means to feed heading material across the path of projection of the nails and from which the "lead-heads" are formed, means to drive the 90 nails through the material to heading position, laterally movable means to form said material about the nail heads, means to move the forming means into and out of operative position, and a pair of spaced coacting guide members disposed beneath said forming means to receive a portion of said nail during the forming operation, said guide members preventing lateral movement of the nail when the forming means is moved laterally to its 95 inoperative position whereby to prevent clogging of said forming means by the finished nail.
- In witness whereof, I have hereunto affixed my hand this 9th day of August, 1929. 100
GEORGE N. WILLIAMS.
